UNITED STATES PATENT OFFICE.

THEODOR KUNDTZ, OF CLEVELAND, OHIO.

DESIGN FOR A SKELETON FRAME FOR DRAWERS.

SPECIFICATION forming part of Design No. 16,882, dated August 31, 1886.

Application filed May 25, 1886. Serial No. 203,250. Term of patent 7 years.

To all whom it may concern:

Be it known that I, THEODOR KUNDTZ, a citizen of the United States, residing at Cleveland, Cuyahoga county, and State of Ohio, have invented and produced a new and original Design for Skeleton Frames for Drawers, of which the following is a specification, reference being had to the accompanying drawings, forming a part thereof.

10 Figure 1 is a side elevation of my newly-designed skeleton frame, showing the drawers in the frame, the central drawer being in position, partly drawn out. Fig. 2 is a front end elevation.

15 The leading or characteristic features of my newly-designed frame are, first, the vertically-disposed series of openings in the side walls of the frame, each opening being parallelogrammic in outline and rounded at the corners, the entire periphery of each opening being beveled, as shown; and, second, the series of horizontally-disposed projections presenting a curved outline in plan view, extending each at regular intervals in a right line across the upright open face or front of the frame. The outer surface of these projections contrast in shade with the remaining surfaces of the frame.

20 C represent side walls of the frame having the vertically-disposed series of openings, each being parallelogrammic in outline, and having rounded corners c, the entire periphery of each opening having an outwardly-extending bevel. The partitions D of the side walls 25 between the rectangular openings, as well as

the entire surface of the wall of the frame, are in a single plane.

E E are a series of horizontal projections curved or semicircular in plan outline, and disposed at regular intervals across the upright 40 open face or front of the frame. They are each respectively in the same horizontal plane in which those portions of the side walls of the frame marked D are situated. The outer surface of the curved or semicircular projections contrasts in shade with the surface of the remainder of the frame.

I claim—

1. In a design for a skeleton frame for drawers, the ornamentation of the same, consisting in the vertically-disposed series of openings in the side walls of the frame, each opening being parallelogrammic in outline and rounded at the corners, as shown and described. 50

2. In a design for a skeleton frame for drawers, the ornamentation of the same, consisting in a series of horizontally-disposed curved projections, extending each in a right line across the upright open face or front 60 of the frame, the outer surface of said projections contrasting in shade with the remaining surfaces of the frame, as shown and described. 55

In testimony whereof I sign this specification, in the presence of two witnesses, this 12th day of May, 1886.

THEODOR KUNDTZ.
